(57) **CLAIM**

I claim the ornamental design for a jewelry element, as shown.

DESCRIPTION

FIG. 1 illustrates a top plan view of a jewelry element of my new design;

FIG. 2 illustrates a bottom view thereof;

FIG. 3 illustrates a front side elevational view thereof, the back side being a mirror image thereof;

FIG. 4 illustrates a right side elevational view thereof, the left side elevational view being a mirror image thereof;

FIG. 5 illustrates a right upper perspective view thereof; and,

FIG. 6 illustrates a right upper perspective view thereof. The broken line illustration of a jewelry ring in FIG. 6 depicts an environmental structure having the jewelry element and is not part of the design sought to be patented. The jewelry element of my new design as illustrated herein is readily embodied in castings for jewelry or cast in a mold.
